UNITED STATES PATENT OFFICE.

ANDREW J. RUSSELL AND ERWIN VAN ALLEN, OF NEW YORK, N. Y.

NON-REFILLABLE BOTTLE.

1,269,313.

Specification of Letters Patent. Patented June 11, 1918.

Application filed July 20, 1917. Serial No. 181,835.

To all whom it may concern:

Be it known that we, ANDREW J. RUSSELL and ERWIN VAN ALLEN, citizens of the United States, residing at New York, respectively, in the county of Bronx, respectively, and State of New York, respectively, have invented new and useful Improvements in Non-Refillable Bottles, of which the following is a specification.

10 This invention relates to non-refillable bottles and has for its principal object the provision of a structure of this character which will include a plurality of valves arranged to operate in the neck of the bottle 15 and disposed whereby they will be freely responsive to the escaping action of the liquid behind same when the bottle is inverted so that the contents can be readily discharged when desired but particularly constructed 20 and mounted so as to positively prevent a re-filling of the bottle after its original contents is discharged therefrom.

A still further object of the invention resides in the provision of a plurality of valves 25 which are so distributed within the neck of the bottle whereby at least one of them will positively close against an inflow of liquid in the neck of the bottle should an attempt be made to re-fill the same.

30 A still further object of the invention resides in the construction of a valve having a double face and a seat correspondingly formed, the former being adapted for swinging and slight sliding movements relatively of the valve so as to insure a positive sealed joint between the valve and the seat when the former is closed.

With the above and other objects in view which will appear as the nature of the invention is better understood, the same consists in the improved construction and novel arrangements of parts which will hereinafter be fully described and particularly pointed out in the claims.

45 In the accompanying drawing, has been illustrated, a single and preferred form of the invention, it being, however, understood that no limitations are necessarily made to the precise structural details therein exhibited, but that changes, alterations and modifications within the scope of the claims 50 may be resorted to when desired.

Figure 1 is a vertical section through the bottle.

55 Fig. 2 is a horizontal section therethrough on line 2-2 of Fig. 1.

Fig. 3 is a sectional perspective view of the body member.

The structure consists of a suitable bottle body 1, having a short interiorly threaded 60 extension 2, in which is fitted and preferably cemented, a correspondingly threaded portion 3, on a metallic shell 4. The latter, through the fact that it is continued directly from the extension 2, constitutes therewith a 65 pouring neck.

The shell is preferably provided with an eye 5, which is adapted to come in juxtaposition with a similar eye 6, on the breast of the bottle body when the shell is fully 70 adjusted upon the extension 2. A seal 7 is then connected between the eyes 5 and 6, and the same is constructed of fragile or other suitable material whereby it will be instantly and permanently destroyed should 75 one tamper with the neck and attempt to remove the shell portion from the body of the bottle.

The shell can be constructed of any well known material. It is tapered from end to 80 end and in fact is substantially of frusto-conical form. Located in the neck above the portion 3, thereof, is a porcelain body 8, which is provided with a set of substantially superposed valve seats 9-9, co-acting 85 with valves 10-10. Similar valve seats 11-11 are associated with valves 12-12, the latter corresponding in form with the valves 11-11. These valves are thus arranged around the neck 4, so that in practice it would be absolutely impossible for all 90 of the same to remain open at the same time should an attempt be made to re-fill the bottle after the original contents is discharged.

Each valve seat is provided with a plurality 95 of valve faces 13 and 14, preferably arranged at an angle of forty-five (45) degrees. All of the seats communicate with each other by way of a substantially sinuous portway 15. The valves are preferably 100 formed of porcelain or other suitable non-corrosive material or material which might act disastrously against the contents of the bottle such as by changing the chemical character of the same. Each of these valves 105 is provided with angular surfaces 16 and 17, which are adapted to co-act with the corresponding angular surfaces of said valve seats so as to insure a perfect sealed joint between each valve and its seat at the 110 requisite moment.

The body member 8, is provided in line

with each valve seat with a socket 18, having a slot 19, which opens toward the seat so as to receive the arm or extension 20, on the next adjacent valve. In this manner 5 each valve is adapted for swinging movement relatively of its seat. The pin-like extension 21, on the arms 20, being confined in the sockets by the walls of the shell 4, which close against the outer open 10 sides of said sockets as shown in Fig. 1. The pin-like portions 21, do not fully occupy the sockets 18, and as a consequence thereof, they are adapted to move laterally therein and in the direction of the 15 valve seats. Each valve is therefore intended to shift laterally or slide slightly over its seat as well as to swing relatively thereof. This arrangement is found most desirable in that the valves are always capable of closing 20 tightly against their seats as will be understood.

The valve seats are disposed with such regard to one another that one of said seats operates as a stop for the next adjacent 25 valve. In this manner, the swinging movement of each valve is limited and even when the bottle is completely inverted, the valves are angularly disposed with relation to their seats and it thus becomes impossible to eff- 30 feet an entrance past the valves should an attempt be made to forcibly convey liquid through the neck for the purpose of re-filling the bottle.

The porcelain plug 8, of the structure is 35 preferably cemented within the metallic shell so as to seal the joint between the latter and the former to prevent leakage. When the shell is operatively in position upon the body of the bottle, the porcelain plug portion is 40 extended into the portion 2, and in order to prevent the metallic portions of the shell from coming in contact with the liquid, the said body 8, is preferably provided with a base flange 22, which underlies the base of 45 the shell and it closes directly against the base of said portion 2, as shown herein. At the point slightly below the upper end of the shell, and arranged interiorly of the latter, is a perforated guard disk 23, which is 50 provided for the purpose of preventing wires or instruments from being inserted

into the presence of the valves. This might be attempted by one desiring to refill the bottle. The said disk is disposed relatively of the next adjacent valve 10—10, so as to 55 form a stop therefor.

The several parts which constitute the bottle are simple of construction, inexpensive to manufacture and admirably designed whereby they can be rapidly assembled with 60 one another and the shell 4, quickly connected with the body of the bottle after the latter has been filled.

What is claimed as new is:—

1. A non-refillable bottle comprising, a 65 shell adapted to be secured to the body of the bottle, a non-metallic body fixedly mounted within the shell and provided with a plurality of relatively staggered seats and a sinuous portway communicating with all 70 of said seats, each of said seats having a plurality of angularly disposed surfaces and valves respectively mounted to slide and swing relatively of the seats and having portions confined in operative position upon 75 said non-metallic body by the shell, each of said valves having a plurality of angularly disposed surfaces adapted to co-act with the corresponding surfaces of the next adjacent seat. 80

2. A non-refillable bottle comprising, a shell adapted to be secured to the body of the bottle, a non-metallic body fixedly mounted within the shell and provided with a plurality of relatively staggered seats and 85 a sinuous portway communicating with all of said seats, each of said seats having a plurality of angularly disposed surfaces and valves respectively mounted to slide and swing relatively of the seats and having portions confined in operative position upon 90 said non-metallic body by the shell, each of said valves having a plurality of angularly disposed surfaces adapted to co-act with the corresponding surfaces of the next adjacent 95 seat, and a perforated guard extending across the shell above the uppermost valve.

In testimony whereof we affix our signatures.

ANDREW J. RUSSELL.
ERWIN VAN ALLEN.
